UNITED STATES PATENT OFFICE.

IGNATZ SALZ, OF NEW YORK, N. Y.

CLIP.

Application filed November 25, 1924. Serial No. 752,094.

To all whom it may concern:

Be it known that I, IGNATZ SALZ, a citizen of the United States, and resident of New York, in the county of New York and State 5 of New York, have invented certain new and useful Improvements in Clips, of which the following is a specification.

This invention relates to improvements in clips of the character commonly employed 10 on the caps of fountain pens and the barrels of fountain pencils to retain these writing implements in the pocket. An object of the invention is to provide attaching means which will secure the clip firmly in place so 15 that it cannot have any movement other than a bending movement at its free end to permit the edge of a pocket to be forced between the clip and the cap or implement.

The retaining means is designed to facilitate 20 the assembly of the clip and the pen cap or pencil barrel and to considerably add to the attractive appearance of the finished product. By virtue of the use of my improved retaining means, the application of 25 the clips may be facilitated and the expense thereof reduced. An escutcheon plate is preferably associated with and forms part of the securing means. Where the attaching means for the clip is in the nature of a substantially U shaped bendable securing device 30 the intermediate portion of which overlies a portion of the fixed end of the clip and the legs of which pass through the clip and cap and are turned over inside the cap, the intermediate portion of the securing device will 35 offer a convenient and conspicuous place for engraving monograms or the like. The ornamental appearance may be greatly enhanced by making the intermediate escutcheon 40 portion of the securing device of some metal which contrasts sharply in color with the metal of the clip.

The invention may be more fully understood from the following description in connection with the accompanying drawings, 45 wherein—

Figure 1 is a disassembled view showing the cap, clip and securing device in elevation.

Figure 2 is a view in side elevation showing the parts assembled.

Figure 3 is a longitudinal sectional view on the line 3—3 of Figure 2.

Figure 4 is an enlarged transverse section on the line 4—4 of Figure 3. 55

Figure 5 is a view similar to Figure 2 but illustrating a slight modification.

For illustrative purposes I have shown the invention as applied to the cap of a fountain pen but it will be evident that the attachment of the clip to a self-feeding pencil or any other similar hollow implement for writing or other purposes which is to be carried in the pocket is within the scope of the invention. 60

The cap 10 may be of conventional construction comprising a cylinder of molded composition having an open end internally threaded at 11 and having its opposite end closed by frictionally fitted plug 12. 13 represents the usual inner sleeve which is frictionally fitted or otherwise secured within the cap and affords a shoulder 14 engageable with some part of the pen barrel (not shown) to limit the telescoping of the cap 70 and barrel, caused by the engagement of threads 11 with suitable threads on the barrel. The sleeve 13 is usually inserted after the clip 16 has been applied. This is particularly desirable in the present instance 75 so because the sleeve offers means for retaining and locking the turned over legs 17 of the U shaped clip securing device 18.

The clip itself may be of substantially conventional construction including a widened 85 approximately flat portion 16^a curved circumferentially in conformity with the curvature of the cap and an offset tapering portion 16^b which terminates in the usual camming knob 16^c held against the exterior of 90 the cap by the inherent resiliency of the metal of the clip. The securing device 18 which I employ is of general U shape having its intermediate portion disposed longitudinally of the clip and having its legs 95 passing through aligned openings 19 in the clip and cap. The intermediate portion of the securing device may if desired, be longitudinally curved in conformity with the curvature of the clip and beveled at its 100 edges, and may either be of the general rectangular shape shown or of any ornamental

conformation such for instance as approximately oval, circular, hour-glass shape, etc. The legs of the securing device may be turned over against the inside surface of the cap by the simple expedient of running a mandrel into the cap. This method of anchoring the securing device is quite advantageous as opposed to the method of riveting wherein considerable pressure may be exerted on the relatively fragile cap to upset the inner end of the rivet.

If the securing device and clip be made of metals of contrasting colors, an attractive ornamental effect is had. For instance, the securing device may be silver and the clip be gold or vice versa, the exposed intermediate portion of the securing device contrasting with the clip and offering a convenient surface upon which initials or other appropriate indicia may be engraved.

After the legs of the securing device have been turned over by ramming a mandrel into the cap the inner sleeve 13 is inserted, this sleeve having a flattened or grooved side 13^a accommodating the turned over ends of the securing device, and effectively locking the securing device against being pried out.

It will be noted that by virtue of the two point engagement of the securing device, the clip is locked to the cap in such a manner that it cannot have pivotal movement on the securing device as in the case where a single round rivet is used.

While I prefer to use securing means in which the bendable legs are integral with the escutcheon plate the legs may be parts separate from the plate, passing through the plate clip, and cap and turned under by a mandrel in the manner above described. The escutcheon plate, especially when of color contrasting with the clip, is a desirable feature, regardless of the manner in which the plate and clip are secured to the cap.

To further enhance the ornamental appearance of the pen, the securing device may serve the double function of retaining the clip in place and clamping between the clip and securing device, a curved ornamental plate 20 which may be shaped as shown to faithfully simulate in connection with the front of the securing device, a bow.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall

be interpreted as illustrative and not in a limiting sense.

Having thus described my invention what I claim as new and desire to secure by Letters Patent is:

1. The combination with a hollow cylindrical member and a spring retaining clip therefor, of means for securing the clip to the member including a pair of bendable securing devices passed through aligned openings in the clip and member, and turned over inside of the cylindrical member, and an escutcheon plate overlying the clip and retained in place by said securing devices.

2. The combination with a hollow cylindrical member and a spring retaining clip therefor, of means for securing the clip to the member including a pair of bendable securing devices passed through aligned openings in the clip and member and turned over inside of the cylindrical member, and an escutcheon plate overlying the clip and retained in place by said securing devices, said escutcheon plate being integral with the securing devices.

3. The combination with a hollow cylindrical member and a spring retaining clip therefor, of means for securing the clip to the member including a pair of bendable securing devices passed through aligned openings in the clip and member and turned over inside of the cylindrical member, and an escutcheon plate overlying the clip and retained in place by said securing devices, said escutcheon plate and clip being of contrastingly colored metals.

4. The combination with a hollow cylindrical member and a spring retaining clip therefor, said clip and said member having a pair of aligned slots therein, of a U shaped securing device including legs passed through the aligned slots and an intermediate portion overlying the clip, said legs being upset within the cylindrical member to prevent displacement of the securing device.

5. The combination with a hollow cylindrical member and a spring retaining clip therefor, said clip and said member having a pair of aligned slots therein, of a U shaped securing device including legs passed through the aligned slots and an intermediate portion overlying the clip, said legs being turned over in the same direction inside of the cylindrical member to prevent withdrawal of the securing device.

6. The combination with a hollow cylindrical member and a spring retaining clip therefor, said clip and said member having a pair of aligned slots therein, of a U shaped securing device including legs passed through the aligned slots and an intermediate portion overlying the clip, said legs being upset within the cylindrical member to prevent displacement of the securing device, the intermediate portion of the secur-

ing device being curved in conformity with the curvature of the cylindrical member.

7. The combination with a fountain pen cap having a pair of parallel slots therein of a spring retaining clip having slots therein aligned with the slots in the cap and a U shaped retaining device including legs passed through the slots and turned over against the inner face of the cap.

10 8. The combination with a fountain pen cap having a pair of parallel transverse slots therein of a clip extending longitudinally of the cap and having slots therein registering with the slots in the cap, a U shaped securing device including legs passed through the aligned slots and turned over against the inner face of the cap and a sleeve fitted in the cap retaining said legs in bent over position.

20 9. The combination with a fountain pen cap having a pair of parallel transverse slots therein of a clip extending longitudinally of the cap and having slots therein registering with the slots in the cap, a U shaped securing device including legs passed through the aligned slots and turned over against the inner face of the cap and a sleeve fitted in the cap retaining said legs in bent over position, said clip and the intermediate portion and securing device being longitudinally curved in conformity with the curvature of the cap.

30 10. The combination with a fountain pen cap having a pair of parallel slots therein of a spring retaining clip having slots therein aligned with the slots in the cap and a U shaped retaining device including legs passed through the slots and turned over

against the inner face of the cap, said securing device and clip being of contrastingly 40 colored metals.

11. The combination with a fountain pen cap having a pair of parallel slots therein of a spring retaining clip having slots therein aligned with the slots in the cap and a U shaped retaining device including legs passed through the slots and turned over 45 against the inner face of the cap, the intermediate portion of said clip being sufficiently wide to offer a surface for the engraving of appropriate indicia.

12. The combination with a fountain pen cap having a pair of parallel slots therein of a spring retaining clip having slots therein aligned with the slots in the cap and a U 55 shaped retaining device including legs passed through the slots and turned over against the inner face of the cap, and an ornamental plate following the curvature of the cap and retained in place by the securing device. 60

13. The combination with a fountain pen cap having a pair of parallel transverse slots therein of a clip extending longitudinally of the cap and having slots therein 65 registering with the slots in the cap, a U shaped securing device including legs passed through the aligned slots and turned over against the inner face of the cap and a sleeve fitted in the cap retaining said legs in bent over position, said sleeve including 70 a flattened portion accommodating the turned over legs of the clip.

Signed at New York, in the county of New York and State of New York, this 21st day of November, A. D. 1924.

IGNATZ SALZ.
